UNITED STATES PATENT OFFICE

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS

DESIGN FOR A SPOON OR ARTICLE OF ANALOGOUS NATURE

Application filed February 25, 1932. Serial No. 42,992. Term of patent 14 years.

To all whom it may concern:

Be it known that I, HAROLD E. NOCK, a citizen of the United States, residing at Newburyport, in the county of Essex and Commonwealth of Massachusetts, have invented a new, original, and ornamental Design for a Spoon or Article of Analogous Nature, of which the following is a specification, reference being had to the accompanying drawings, forming a part thereof.

In the accompanying drawings, Figures 1, 2 and 3 are views, in front, side and rear elevations, respectively, of a spoon showing my new design, and Figures 4 and 5 are views,

showing the handle in cross-section, on the lines 4—4 and 5—5 respectively of Figure 1.

The design is delineated as embodied in the handle of a spoon but it is contemplated that the design may also be embodied in or applied to the handles of forks, knives, servers and other analogous pieces of flatware which may form part of a table service of uniform pattern.

I claim:

The ornamental design for a spoon or article of analogous nature, substantially as shown and described.

HAROLD E. NOCK.
